UNITED STATES PATENT OFFICE

155,529

DESIGN FOR A TEXTILE FABRIC OR SIMILAR ARTICLE

Robert E. Minger, Manhattan Beach, Calif., assignor to Mabs, Inc., Los Angeles, Calif., a corporation of California

Application February 19, 1949, Serial No. 968

Term of patent 3½ years

(Cl. D92—1)

To all whom it may concern:

Be it known that I, Robert E. Minger, a citizen of the United States, residing at Manhattan Beach, county of Los Angeles, and State of California, have invented a new, original, and ornamental Design for a Textile Fabric or Similar Article, of which the following is a specification, reference being had to the accompanying drawing, forming part thereof.

The figure is a plan view of a piece of textile fabric or similar article embodying my new design, the repeat unit of which is contained between the dash lines. The design unit is repeated horizontally and vertically as indicated on the drawing.

I claim:

The ornamental design for a textile fabric or similar article, substantially as shown and described.

ROBERT E. MINGER.
